(57) **CLAIM**

The ornamental design for a controller for railway vehicle as shown and described.

DESCRIPTION

FIG. 1 is a perspective view of a controller for railway vehicle showing our new design;

FIG. 2 is a front view thereof;

FIG. 3 is a rear view thereof;

FIG. 4 is a top plan view thereof;

FIG. 5 is a bottom view thereof;

FIG. 6 is a right side view thereof;

FIG. 7 is a left side view thereof;

FIG. 8 is an enlarged view of a part 8-8 in FIG. 2 thereof;

FIG. 9 is an enlarged view of a part 9-9 in FIG. 4 thereof;

FIG. 10 is an enlarged view of a part 10-10 in FIG. 4 thereof;

FIG. 11 is an enlarged view of a part 11-11 in FIG. 4 thereof; and,

FIG. 12 is an enlarged view of a part 12-12 in FIG. 7 thereof;

The broken lines immediately adjacent to the shaded areas depict the bounds of the claimed design, while all other broken lines are directed to environment. The broken lines form no part of the claimed design.
